SHADE ROLLER OPERATING DEVICE

Frank H. Toms, Detroit, Mich.

Application June 6, 1947, Serial No. 753,137

7 Claims. (Cl. 160—301)

1

This invention relates to shade rollers, and in particular to operating mechanisms for shade rollers.

One object of this invention is to provide an operating mechanism for a shade roller which will operate smoothly and dependably to halt the shade roller at any desired point, or to cause it to wind up the roller blind smoothly and rapidly, at the will of the operator.

Another object is to provide an operating mechanism for a shade roller which will provide a positive locking action at a multiplicity of positions during a single revolution of the shade roller.

Another object is to provide an operating mechanism for a shade roller, including a rotating multi-lobe cam or ratchet wheel cooperating with a roughly C-shaped pawl which is pivoted intermediate its ends and encircles the cam or ratchet wheel, a stop cooperating with the pawl to limit its range of motion, the foregoing mechanism being compact, yet positive in its engagement and disengagement as the roller blind is halted or rolled up.

Another object is to provide an operating mechanism for a shade roller, as set forth in the object immediately preceding, wherein the pawl has a weighted hook and which engages the cam or ratchet wheel, and it slightly overbalances the weight of the remainder of the pawl on the opposite side of its pivot, so that the action of gravity will cause the hook portion to engage and lock the cam or ratchet when the hook portion is uppermost, whereas centrifugal force will counterbalance the gravitational force and unlock the cam or ratchet when the hook portion is underneath the cam or ratchet and the roller is rotated rapidly upward from that point.

Another object is to provide an operating mechanism for a shade roller, as set forth in the preceding objects, having elements which do not accidentally slip, but which releasably lock when it is desired to halt the shade roller at any particular location, the shade roller being wound up by means of a spring within the roller barrel when the pawl is released from the cam or ratchet.

In the drawings:

Figure 1 is a side elevation, partly in central vertical longitudinal section, of a shade roller having an improved operating mechanism, according to a preferred form of the present invention;

Figure 2 is a left-hand end elevation of the operating mechanism shown in Figure 1, with the parts thereof in their locked positions;

2

Figure 3 is a horizontal section along the line 3—3 in Figure 1;

Figure 4 is a vertical cross-section along the line 4—4 in Figure 1; and

Figure 5 is a left-hand elevation of the roller operating mechanism, similar to Figure 2, but showing the parts in their unlocked positions, whereby the shade roller may be freely rolled up.

Referring to the drawings in detail, Figure 1 shows a shade roller, generally designated 10, having at its left-hand end the novel operating mechanism, generally designated 11, which is the subject of the present invention. The shade roller 10 consists of the usual barrel 12, customarily of wood and having at its right-hand end a cap 13 which carries a pin 14 of circular cross-section, secured in the end of the cap 13. The pin 14 is journaled in the usual bore 15 in the central portion 16 of an arm 17 forming part of an L-shaped bracket 18, which is secured in the usual way to the window frame.

Mounted on the barrel 12 is the usual roller blind 19 of sheet material, such as fabric, and secured at its inner end by any suitable means, such as carpet tacks (not shown). The barrel 12 is provided with an axial bore 20 which extends inward to an end wall 21 (Figure 1) and which is closed at its outer end by a cap 22 having indentations 23 penetrating the wood and locking the cap 22 in position. The end wall of the cap 22 is provided with a bore 25 in which is mounted a bushing 26. The inner end of the bushing 26 is flanged, and its outer end flared into a conical opening 27 in a supporting disc 28, so as to secure the disc 28 firmly and fixedly to the end wall of the end cap 22. A rivet 28a (Figure 3) passing through the disc 28 and end wall 24 prevents relative rotation therebetween. Journaled in the bore 29 of the bushing 26

40 (Figure 1) is a shaft or pin 30 of rectangular cross-section, as seen from a comparison of Figures 1 and 3, and the end elevation of Figures 2 and 5.

The pin 30 is pointed at its inner end 31, to enable it to be driven into the end of a rod 32 of wood or the like. A cup-shaped ferrule 33 covers the outer end of the rod 32 and is bored centrally for the passage of the shaft or pin 30. The ferrule 33 is provided with a pair of bent-over projections 34 diametrically opposite one another and serving as an anchorage for the outer end of a coil spring 35. The coil spring 35 is of such diameter as to fit freely into the bore 26 of the barrel 12, and has its inner end anchored as at 36 to a plug 37 of wood or the like occupying the inner end of the bore 26 and

secured therein as by the mark 38. The plug 37 is provided with a cylindrical recess or cavity 39 in which the inner end of the rod 32 is rotatably journaled.

Mounted on the pin or shaft 30 of rectangular cross-section and outwardly from the supporting disc 28 is a multi-lobe cam or ratchet wheel 40 (Figure 2) having a multiplicity of teeth or lobes 41, each of which has an outwardly curving portion 42 and a radially shouldered portion 43. The ratchet wheel or cam 40 is, of course, provided with an elongated central hole fitting the elongated cross-section of the pin or shaft 30, the latter being widened, as at 44, to retain the ratchet or cam 40 in position. The shaft or pin 30 at its outer end is slightly narrowed, as at 45, and fits into a slot 46 in an arm 47 of a conventional end bracket 48 of angle or L-shaped form. The brackets 18 and 48 are secured to the window frame in any suitable manner, as by fasteners 49.

Mounted near the periphery of the supporting disc 28 is a pivot pin 50 which passes through a hole 51 in a C-shaped pawl 52, so as to pivotally mount the latter upon the former. The pawl 52 has a beak-like hooked end 53 at one end thereof, with a point 54 engageable with the ratchet portions 43. The hook portion 53 is thickened, as shown in Figure 3, to give it increased weight. The remainder of the pawl 52 between the edge of the thickened or weighted hook portion 53 is relatively thin and encircles the cam or ratchet wheel 40, and is provided with a cutaway portion 55 (Figures 2 and 5) for that purpose. The pawl 52 remote from its pivot 50 and pointed or hooked portion 53, is of reduced width and is provided with a movable stop portion 57 which is of approximately U-shaped form, and which interlocks with an approximately U-shaped fixed stop member 58 (Figures 2 and 5).

The movable and fixed stops 57 and 58 are provided with ends 59 and 60 respectively, which are so angled as to flatly engage one another (Figure 5) when the hook portion 53 swings around its pivot pin 50 out of engagement with the radially-shouldered portions 43 of the cam or ratchet wheel 40. The shank 61 of the fixed stop 58 is provided with a widened base portion 62 which is secured by fasteners, such as rivets 63, to the supporting disc 28.

In the operation of the shade roller 10, equipped with the improved operating mechanism 11 of the present invention, let it be assumed that the roller blind 19 is at the top of its run so as to be fully wound upon the barrel 12. To draw the shade the user merely grasps the roller blind 19 and pulls downward upon it, rotating the barrel 12. As the barrel 12 rotates in a counterclockwise direction (Figures 2 and 5) the ratchet wheel or cam 40 remains fixed, due to the locked engagement of the pin or shaft 30 in the slot 46 of the bracket 48. During rotation of the disc 28 with the roller 12, the C-shaped pawl 52 rotates around the fixed cam or ratchet wheel 40, the pointed or hooked portion 53 slipping over the curved portions 42 of the teeth 41 and clicking past the shoulder portions 43 thereof. Thus, the roller blind 19 may be drawn freely downward to its full length without encountering any substantial resistance.

When the roller blind 19 is released, the weighted hook portion 53 moves around the ratchet wheel 40 until it arrives above the latter, whereupon its overbalancing weight will cause its point 54 to drop into engagement with one of

the upper-most shouldered portions 53 of the teeth 41, the coil spring 35 forcing these into locking engagement. To unlock the shade roller and permit it to move upward, the operator pulls downward upon the roller blind 19 until the weighted hook portion 53 moves underneath the cam or ratchet 40. The over-balancing weight of the hook portion 53 then causes it to swing downward, as shown in Figure 5, causing the point 54 to disengage itself from the shouldered portion 43 of the teeth 41 with which it was previously engaged. This releases the locking engagement between the pawl 52 and ratchet 40, whereupon the operator releases the roller blind 19 while still retaining a grip upon it, so that the roller blind 19 moves upward with a rapid motion.

As a consequence of the rapid rotation of the barrel 12 and disc 28, centrifugal force acting on the weighted hook portion 53 develops as the latter moves from beneath to above the ratchet 40 and counteracts the effect of gravity, causing the point 54 to remain above the teeth 41 as it passes over the top of them, preventing locking therebetween.

If, however, the operator desires to halt the shade roller at any intermediate point, he merely pulls back on the roller blind 19 against the urge of the spring 35 to roll it up, causing the rotation of the barrel 12 to slow down. When this occurs, the centrifugal force acting upon the weighted hook portion 53 diminishes to the point where the weight of the portion 53 overbalances it, causing the point 54 to drop into engagement with one of the shoulders 43 on one of the upper teeth 41. This locks the shade roller in its intermediate position.

Thus, when the shade roller is released so as to move upward rapidly, centrifugal force overcomes the gravity upon the weighted portion 53 and permits the mechanism to remain unlocked. If, however, the operator slows down the winding up of the roller blind 19, the centrifugal force is reduced to the point where the weight of the weighted portion 53 overbalances and locking occurs.

What I claim is:

1. An operating device for a shade roller having an internal operating spring and shaft, said operating device comprising a ratchet wheel connected to said shaft and having multiple teeth thereon, a pawl pivotally mounted on the end of said roller and having a shank extending partway around the periphery of said ratchet wheel, said pawl having a weighted tip engageable with the teeth of said ratchet wheel, and a fixed stop on the end of said roller engageable with said pawl for limiting the pivotal motion thereof, said shank having a hooked end portion engaging said stop.

2. An operating device for a shade roller having an internal operating spring and shaft, said operating device comprising a ratchet wheel connected to said shaft and having multiple teeth thereon, a pawl pivotally mounted on the end of said roller and having a shank extending partway around the periphery of said ratchet wheel, said pawl having a weighted tip engageable with the teeth of said ratchet wheel, and a stop on the end of said roller engageable with said pawl for limiting the pivotal motion thereof, said stop having a hooked end portion and said shank also having a hooked end portion engageable with the hooked end portion of said stop.

3. An operating device for a shade roller having an internal operating spring and shaft, said

operating device comprising a ratchet wheel connected to said shaft and having multiple teeth thereon, a pawl pivotally mounted on the end of said roller and having a shank extending partway around the periphery of said ratchet wheel, said pawl having a weighted tip engageable with the teeth of said ratchet wheel, and a stop on the end of said roller engageable with said pawl for limiting the pivotal motion thereof, said stop and said shank having approximately C-shaped end portions lying one within the other with their extremities in engagement with one another in the unlocked position of said pawl.

4. An operating device for a shade roller having an internal operating spring and shaft, said operating device comprising a ratchet wheel connected to said shaft and having multiple teeth thereon, a pawl pivotally mounted on the end of said roller and having a shank extending partway around the periphery of said ratchet wheel, said pawl having a tip engageable with the teeth of said ratchet wheel, and a stop on the end of said roller engageable with said pawl for limiting the pivotal motion thereof, said shank having a hooked end portion engageable with said stop, the tip of said pawl having a weight thereon arranged to overbalance the weight of the shank of said pawl on the opposite side of the pivot thereof.

5. An operating device for a shade roller having an internal operating spring and shaft, said operating device comprising a ratchet wheel connected to said shaft and having multiple teeth thereon, a pawl pivotally mounted on the end of said roller and having a shank extending partway around the periphery of said ratchet wheel, said pawl having a tip engageable with the teeth of said ratchet wheel, and a stop on the end of said roller engageable with said pawl for limiting the pivotal motion thereof, said stop having a hooked end portion and said shank also having a hooked end portion engageable with the hooked end portion of said stop, the tip of said pawl having a weight thereon arranged to overbalance the weight of the shank of said pawl on the opposite side of the pivot thereof.

6. An operating device for a shade roller having an internal operating spring and shaft, said

operating device comprising a ratchet wheel connected to said shaft and having multiple teeth thereon, a pawl pivotally mounted on the end of said roller and having a shank extending partway around the periphery of said ratchet wheel, said pawl having a tip engageable with the teeth of said ratchet wheel, and a stop on the end of said roller engageable with said pawl for limiting the pivotal motion thereof, said stop and said shank having approximately C-shaped end portions lying one within the other with their extremities in engagement with one another in the unlocked position of said pawl, the tip of said pawl having a weight thereon arranged to overbalance the weight of the shank of said pawl on the opposite side of the pivot thereof.

7. An operating device for a shade roller having an internal operating spring and shaft, said operating device comprising a ratchet wheel connected to said shaft and having multiple teeth thereon, a pawl pivotally mounted on the end of said roller and having a shank extending partway around the periphery of said ratchet wheel, said pawl having a weighted tip engageable with the teeth of said ratchet wheel, and a stop on the end of said roller engageable with said pawl for limiting the pivotal motion thereof, said stop and said shank having approximately C-shaped end portions lying one within the other with their extremities in engagement with one another in the unlocked position of said pawl, said extremities being inclined relatively to the adjacent portions of said stop and said shank respectively.
